United States Patent Office.

JOHN BEATTIE, OF CHICAGO, ILLINOIS, ASSIGNOR TO WILLIAM BAKER, OF SAME PLACE.

Letters Patent No. 92,250, dated July 6, 1869.

IMPROVED HOISTING-APPARATUS.

The Schedule referred to in these Letters Patent and making part of the same

To all whom it will concern:

Be it known that I, JOHN BEATTIE, of Chicago, in the county of Cook, and State of Illinois, have invented a new and improved Hoisting-Apparatus; and I do hereby declare that the following is a full, clear, and exact description thereof, which will enable others skilled in the art to make and use the same, reference being had to the accompanying drawings, forming part of this specification.

This invention relates to an improved hoisting-apparatus, which may be employed for unloading grain, in bulk, from ears, and consists in an improved arrangement of means for gearing and ungearing the main winding-drum with the driving-shaft; also, in a guiding-arrangement for the main rope.

Figure 1 represents a plan view of my improved apparatus, and

Figure 2 represents a transverse section on the line *x x* of fig. 1.

A represents the main winding-drum, and B, the chain or rope working over the same, and moving the grain-carrying device.

To the said drum, on one side thereof, two smaller drums, C and D, are connected, and all capable of working loosely on the driving-shaft E, when not in gear with the clutch F, splined to the shaft, and arranged to engage with the main drum A, on the side opposite to the drums C and D.

G represents a bell-crank, pivoted to the framing, and connected to the clutch F, for the purpose of throwing it into and out of gear with the drum.

The long arm of the bell-crank is connected, by a chain, H, to the drum D, and by a cord, I, to a weight, K, suspended over the grooved pulley L. These are intended to move the bell-crank, alternately, in opposite directions; and a latch, M, is provided, to hold the bell-crank in the position to maintain the clutch out of gear with the drum A.

N represents a tappet-wheel, arranged on the end of the drum D, for raising the latch M, for disengaging the bell-crank G, and

O represents a cord, wound upon the drum C in the direction opposite to that in which the chain H is wound on the drum D, and carried, over the pulley P, to the weight Q, suspended thereon.

When the main rope has been drawn out sufficiently for the work required, it is slightly slackened, to allow the weight Q to draw the drums backward sufficiently

to cause one of the tappets on the wheel N to strike the short end of the catch M, and raise it, to disconnect the bell-crank, and allow the weight K to draw it back, and throw the clutch P into gear with the drum A, thereby setting it into motion, (the said clutch being always revolving with the shaft E,) to wind the rope B, and move the grain.

The chain H is provided with a sufficient amount of slack to permit the rope B to be wound up sufficiently before the said chain becomes taut, at which time it will move the bell-crank inward, and throw the clutch out of gear with the drum, when the latter ceases to rotate, and the latch will catch the bell-crank, and hold it in this position.

In order to allow the tappet-wheel N to revolve in one direction past the end of the catch M, without any effect thereon, the latter is provided with an articulated tappet, S, which will rise, and let the tappets pass, when the wheel is moving one way, but will bear against a lug or shoulder of the catch, which maintains it in the path of the tappets of the wheel, when moving in the other direction.

By this arrangement, the main rope B may be drawn out to any desired distance, and the clutch be caused to gear with the drum for winding up with the same facility.

The main rope is provided, at the end of its guide, with a system of guide-rollers, *a b c*, arranged to guide it in three directions, to prevent entanglement, and facilitate the working of the rope in any direction.

Having thus described my invention,

I claim as new, and desire to secure by Letters Patent—

1. The improved method of gearing and ungearing the clutch F and drum A, by means of the drums C and D, actuated as described, the tappet-wheel N, and catch M, chain H, and weighted cord I, all substantially as and for the purpose specified.

2. The combination, with the drum A, bell-crank, and clutch, of the drum C, weighted cord O, tappet-wheel N, latch M, and weighted cord I.

The above specification of my invention signed by me, this 30th day of October, 1868.

JOHN BEATTIE.
